United States Patent Office

Des. 233,766
Patented Nov. 26, 1974

233,766

WATER PIPE

William John Lobnitz, 9922 Pillsbury Ave. S.,
Bloomington, Minn. 55420

Filed May 21, 1973, Ser. No. 362,513

Term of patent 14 years

Int. Cl. D27—02

U.S. Cl. D27—3

FIG. 4

FIG. 3

FIG. 1

FIG. 2

FIG. 5

FIG. 1 is a right side elevational view of a water pipe showing my new design;

FIG. 2 is a rear elevational view;

FIG. 3 is a front elevational view;

FIG. 4 is a top plan view thereof; and

FIG. 5 is a bottom plan view thereof.

I claim:

The ornamental design for a water pipe, substantially as shown.
